UNITED STATES PATENT OFFICE.

MARTIN HEMLEB, OF ELIZABETH, NEW JERSEY, ASSIGNOR TO THE SINGER MANUFACTURING COMPANY, A CORPORATION OF NEW JERSEY.

BLINDSTITCHING-MACHINE.

1,069,010.

Specification of Letters Patent.

Patented July 29, 1913.

Application filed November 9, 1907. Serial No. 401,367.

To all whom it may concern:

Be it known that I, MARTIN HEMLEB, a citizen of the United States, residing at Elizabeth, in the county of Union and State 5 of New Jersey, have invented certain new and useful Improvements in Blindstitching-Machines, of which the following is a specification, reference being had therein to the accompanying drawings.

- 10 Many machines have been devised in the past several years for performing blindstitching upon the hems at the bottoms of the legs of trousers and for general operations of this class, all of which have been 15 open to certain more or less serious objections. One of the chief requirements for successful work of this character has been found to be operation upon superposed plies of fabric with the minimum amount of dis- 20 tortion at the stitching point, and the present improvement is embodied in a machine in which the material adjacent the stitching point is permitted to lie substantially flat and undistorted, excepting at the point en- 25 tered by the needle, which is subjected to a slight crimping action to present the fabric in the most favorable position to receive the needle.

In its preferred form, the frame of the 30 machine is constructed with the usual bracket-arm overhanging a narrow work-sustaining horn or bed of substantially oval shape adapted to enter small hollow articles. The curved needle is carried by a 35 vibrating needle-arm fulcrumed in the head of the bracket-arm, which is provided with a depending bearing bracket in which is journaled the horizontal rotary hook-shaft provided with a loop-taking hook adapted to 40 co-operate with the needle and having an axial thread-cavity containing a bobbin case, a space being provided in front of the hook for access to the contained bobbin to permit the renewal of the secondary thread sup- 45 ply without disturbing the hook, which is connected by suitable gearing with the forward portion of the main-shaft to rotate at twice the speed of the latter.

To provide clearance for the body of the 50 work between the stitching point and the upright portion of the frame, the forward portion of the work-sustaining horn is elevated adjacent to the needle-path and a vertically moving work-support is slidingly 55 mounted in such outer portion of the horn

and provided with a work-engaging rib disposed transversely of the horn, to which rib is fitted the lower operative face of the spring-actuated presser-foot, the work-support having a short projection directly beneath the needle-path for crimping the work, which projection is received within a corresponding recess in the operative face of the presser-foot. The work-support is provided with feed openings to receive the 60 feed-dog which is actuated for each stitch-forming operation, while the work-support is successively raised and lowered for consecutive stitch-forming operations to insure the formation of stitches alternately 65 through and above the fabric in the production of an overseam, the raising of the work-support serving to lift the fabric clear of the feed-dog so as to rob the same of its normal action upon the fabric for each alter- 70 nate stitch-forming operation.

The invention will be understood by reference to the annexed drawings, in which—

Figure 1 is a side elevation, partly in section, and Fig. 2 is a plan of a machine embodying the present improvements. Fig. 3 is a front elevation of the machine with the face-plate and end cap of the work-sustaining horn removed, Fig. 4 a transverse section of the same midway of the frame, 80 and looking forwardly, and Fig. 5 the bottom view of the machine. Fig. 6 is a sectional elevation of the machine through the upright portion of the bracket-arm and looking rearwardly. Fig. 7 is a perspective 85 view of the forward portion of the machine. Fig. 8 is a perspective view of a portion of the feed controlling mechanism, and Fig. 9 a similar view of the feed regulating lever. Fig. 10 is a perspective 90 view of the work-support. Figs. 11 and 12 are perspective views of the presser-foot. Fig. 13 is a perspective view of the stitch-forming members detached from other portions of the machine. Figs. 14 and 15 95 are sectional views, upon a larger scale than the other views, representing the needle in two positions in relation to the work. Figs. 16 and 17 are detached edge and side views 100 of the work-support actuating levers.

The frame of the machine comprises the usual bracket-arm formed with a horizontal portion 1 having the head 2 at its forward end and the upright portion 3 at its rearward end which is bolted to the base portion 110

3^x which has a forwardly extending work-supporting horn or bed 4 with raised outer end 5. The base is provided with a series of feet 3^{xx} extending outwardly below the 5 lower side of the horn 4 whereby the latter is spaced above the point of support of the machine frame upon the work table to which it is bolted, so as to permit of the stitching of tubular articles of comparatively small 10 size, such as the sleeves or legs of garments. The main-shaft 6 is journaled longitudinally in the bracket-arm 1 and carries at its rearward end the usual balance-wheel 7 and pulley-wheel 8 and at its forward end the 15 crank-disk 9 provided with a cylindrical crank-pin 10 and offset ball-crank pin 11. To the crank-pin 10 is connected the extremity of one arm 12 of a bellcrank take-up lever having a second arm 13 in angular 20 relation thereto and provided with a thread-eye 14, said bellcrank lever being pivoted at the junction of its arms by the pin 15 to one end of a swinging lever 16 having a fixed fulcrum 17 within the head 2 of the bracket- 25 arm.

The ball-crank pin 11 is connected by means of a pitman 18 with a ball-stud 19 at the angle of the bent needle-lever 20 having a fulcrum-pin 21 within the head 2 of 30 the bracket-arm and disposed transversely of the main-shaft, the needle-lever being provided at its lower end with a transverse needle-socket in which is secured by means of the clamp-screw 22 the shank of the needle 23 curved concentrically with the fulcrum-pin 21.

The bracket-arm adjacent the head 2 is provided with a depending plate 24 having bearing bosses 25 in which is journaled the 40 horizontal hook-shaft 26 provided at its forward end with a revolving hook 27 disposed above the path of circular reciprocatory movement of the needle, and provided in its forward face with an axial thread-case cavity 45 within which is fitted the usual thread-case 28 having a notch 29 entered by the holding arm 30 and itself provided with a central thread-cavity having an axial bobbin supporting pin 31 to receive the removable secondary-thread-bobbin 32. The bobbin 50 may be removably applied to the thread-case in the manner represented in the patent to P. Diehl No. 815,517, dated March 20, 1906. Extending beneath the needle-path 55 and opposite the path of movement of the beak of the hook is the fixed needle-guide 25^a whose shank 25^b is secured by means of the fastening screw 25^c to the forward hook-shaft bearing 25.

The rearward portion of the hook-shaft 26 is provided with an angular gear 33 meshing with a similar gear 34 at the lower end of an intermediate shaft 35 journaled in suitable bearings projecting from the plate 65 34 and having at its upper end an angular

gear 36 meshing with a similar gear 37, but of twice the diameter, mounted upon the forward portion of the main-shaft 6, whereby the hook receives two rotations for each rotation of the main-shaft.

The cavity for the moving parts disposed within the head is closed by means of the usual face-plate 38, and the gearing adjacent the bearing bosses 25 is housed by the cap 39, while the gears 36 and 37 are 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 suitable bearings within the horn 4 and is provided at its forward end with an upwardly extending arm 69 provided with parallel guideways 70 to which are fitted the 5 opposite edges of a slide-block 71 to the upper end of which is pivotally connected by means of the screw-stud 72 the feed-dog 73 having four rectangularly arranged feeding sections corresponding with the apertures 45 of the work-support and passing through the same for engagement with the under side of the work. The slide-block 71 is provided with a transverse slot 74 entered by a stud 75 carried by a lateral arm 76 of 10 the feed-lifting rock-shaft 77 journaled within the horn 4 and provided at its rearward end with a lateral arm 78 having a pivotal connection with the lower end of a pitman 79 whose opposite end is formed 15 with a strap 80 embracing the usual actuating eccentric 81 on the main-shaft 6. The rearward end of the feed-rock-shaft 68 is provided with a lateral arm 82 pivotally connected with the lower end of the feed- 20 actuating lever 83 having at its opposite end the usual yoke 84 embracing the slide-block 85 surrounding the feed-actuating eccentric 86 upon the main-shaft; the lever 83 having beneath its lug the lateral fulcrum- 25 stud 87 entering a slide-block 88 fitted to the slideway 89 in the feed-regulating lever 90 which is fulcrumed by means of the lateral stud 91 upon the lug 92 within the bracket-arm and extends transversely of the 30 latter through the usual slot 93 and is provided at its outer end with a set-screw 94 serving as a finger-piece for moving the lever and as a holding means by engagement of the point of the screw with the side of 35 the housing 95 for the gears 62 and 63, which is in practice provided with a cap 96. The feed lifting and advancing eccentrics being mounted upon the main-shaft, effect an operative or feeding movement of the 40 feed-dog for each reciprocation of the needle, while the cam-member 61, turning at one-half the speed of the main-shaft, and imparting a single up-and-down movement to the work-support for each rotation, produces alternately a rising and a falling 45 movement of the work-support preparatory to the production of each stitch, thus causing it to perform its cycle of movements with one-half the frequency of the feed-dog. 50 Opposed to the work-support 43 is the presser-foot 97 having its under or operative face arched to fit the work bending rib 44 of the work-support, and provided with a transverse needle-slot 98 and adjacent recess 55 99 to receive the work-crimping member 46 of the work-support. The presser-foot is provided at the front upon one side of its center with a notch forming a longitudinal guide-shoulder 100 and an inclined undercut 60 105 work-smoothing shoulder 101. The shank 65

of the presser-foot 97 is secured in the usual manner to a presser-bar 102 mounted in the head 2 of the bracket-arm and provided with a collar 103 having a lateral lug 104 engaged by the cam portion 105 of the lifting lever 106 pivotally mounted in the fixed stud-screw 107. Secured in the collar 103 is the usual guide-rod 108 surrounded by the presser-bar spring 109 interposed between the collar 103 and the usual bushing 110 at 70 the top of the head 2 of the bracket-arm, the spring 109 serving to maintain the presser-foot 97 pressed upon the material interposed between the same and the work-support 43. The needle-slot 98 is of greater 75 depth than the throw of the lifting cam 105, whereby the accidental lifting of the presser-foot while the needle is in the material is prevented from breaking or injuring the needle. 80

In the operation of the machine, the work, as for instance, the tubular portion of a garment having the body portion *a* turned over along one margin to form a hem *b* with raw edge *c*, is introduced between the work-support and the presser-foot, with the hem at the right and the raw edge *c* lying against the guide-shoulder 100. As represented in Fig. 7, a portion of such a seam has been 85 stitched, and the presser-foot then elevated for purposes of illustration. The presser-foot having been lowered, the machine is started. In forming the initial stitch the work-support is preferably raised and the the first thrust of the needle is partially 90 through the body-fabric and through raw edge of the hem as represented in Fig. 14, the loop-taker seizing the thread-loop from the needle and casting it about its mass of secondary thread in the usual manner and the stitch being set by the take-up acting 95 upon the primary or needle-thread. As the roller-stud 59 passes beyond the end of the outer portion of the cam-groove 60, as represented in Figs. 3 and 6, the work-support 100 is lowered and the feed-dog rises through its slots 45 into engagement with the work which it advances a stitch-length and then drops out of engagement. 105

The operation of the work-engaging portions of the feed-dog through the parallel apertures 45 in alinement with the work-crimping member 46 enables the feed-dog to engage the work in substantial alinement with the stitching so as to insure precision in 115 the advance of the work, while the formation of the work-bending rib 44 with a flat top and the construction of the arched operative face of the feed-dog to conform therewith permits the upper serrated portions of the feed-dog to be made substantially flat so as to avoid crowding the stitched portion of the fabric together as would be effected by laterally inclining the serrated feeding surfaces correspondingly 120 125 130 135

with the face of the presser-foot at opposite sides of the recess 99 so as to impair the flatness of the finished seam. In its next thrust, the needle passes over the top of the body fabric and hem as represented in Fig. 15, and the overedge stitch is formed. As the feed-dog rises for a second feeding action, and before its advance movement begins, the work-support rises and lifts the work above the feeding surface, whereby the advance movement of the feed-dog fails to advance the work, and the subsequent thrust of the needle again takes place through the work as represented in Fig. 14, and beneath its previous thrust. The operations of the parts as thus described are repeated throughout the length of the seam.

While the timing of the work-support actuating cam as above described causes the work to be raised above the operative surface of the feed-dog for each alternate stitch, it is evident that by shortening the outer portion of the cam-groove 60 and properly locating the same, the lifting of the work-support may be effected between feeding movements of the feed-dog, whereby the material will be advanced a stitch length for each thrust of the needle.

As will be readily seen, the bending of the work by means of the tapered rib 44 of the work-support and arched lower face of the presser-foot is not effected to facilitate the stitching operation, but its object is to raise the stitching point sufficiently above the top of the work-sustaining horn or bed to provide ample clearance for the various thicknesses of work to enable it to be readily introduced and removed from the machine, the crimping of the work for the stitching operation being effected by the crimping member 46 of the work-support 33 in conjunction with the recess 99 in the presser-foot. In other words, the taper form of the rib 44 is provided merely to afford a raised seat or projection for the crimping member 46 above the plane of the body of the material which is supported somewhat below the gear casing 39 for clearance and convenience in handling the work. While the taper form of the rib 44 is obviously very desirable to obviate the distortion of the material by abrupt rectangular bends, it is equally desirable that the feeding surface of the feed-dog should be at right angles to its pressure upon the goods to prevent crowding of the same toward the central line of the seam, and this has been accomplished by flattening that portion of the bending rib 44 through which the feed-dog rises for engagement with the work.

It has been proposed heretofore in blind stitching machines of the present type to mount the loop-taker in a removable bracket in order to provide access for renewal of the secondary thread supply. According to the

present improvement, the loop-taker is mounted in a fixed bracket permanently attached to and depending from the bracket-arm, and clearance is provided in front of the loop-taker for access to the bobbin, 70 which is adapted to be inserted and removed without disturbing the hook, which latter is therefore adapted to be accurately located in reference to the needle-path, the needle-lever being shown in the present instance formed in two relatively adjustable parts 20 and 20^a connected by means of a fastening screw 20^b, as represented in Fig. 14.

As previously stated, the arching of the operative faces of the work-support and presser-foot elevates the stitching point, so that the positions of the needle and the loop-taker may be correspondingly elevated, while the dropping of the body of the work-supporting horn or bed intermediate the stitching position and the face of the bracket-arm provides ample clearance for the body of the goods in the blind stitching of garments and other articles at a distance from the margin. It will therefore be seen that the 90 general form of the frame and location of the operative parts adapts the machine for general use for all classes of blind-stitch work, and renders its scope of operation as broad as that of the ordinary straight-ahead 95 stitching machines, which has, it is believed, never been attained with any other blind-stitching machine heretofore devised.

While the thread-case holding arm 30 may be made stationary, it is herein represented as adapted to receive a slight thread releasing movement similarly to the lower thread controller of my United States Patent No. 785,168, dated March 21, 1905.

Having thus set forth the nature of the 105 invention what I claim herein is:—

1. In a blind stitching machine, the combination with a frame comprising a bracket-arm and a work-supporting bed, and a main-shaft journaled in the bracket-arm, of a 110 vibrating needle-carrier fulcrumed upon the bracket-arm and movable in a plane substantially parallel with the main-shaft, a needle mounted in said carrier, a circularly moving loop-taker mounted in bearings depending from the bracket-arm upon an axis parallel with the main-shaft and having a beak whose path of movement is transverse to that of the needle, a work-crimping member movable toward and from the path of 115 reciprocation of said needle, an adjacent feed-dog, means for imparting to said feed-dog feeding and rising and falling movements for each stitch, and means for imparting to said crimping member rising and 120 falling movements of less frequency than those of the feed-dog.

2. In a blind-stitching machine, the combination with a frame comprising a bracket-arm and a work-supporting bed adapted 130

- for attachment to a work table, and a base above the bottom of which the lower side of the bed is spaced to afford a clear work-receiving space between the bed and the 5 work table, a main-shaft journaled in the bracket-arm, and stitch-forming mechanism comprising a reciprocating needle and a co-operating loop-taker both sustained by the bracket-arm and operatively connected with 10 the forward portion of the main-shaft, of a work-crimping member movable toward and from the path of reciprocation of said needle and an adjacent feed-dog, both mounted within said work-supporting bed, a 15 cam-member mounted in said bracket-arm and operatively connected with the main-shaft to rotate at a slower speed, and operative connections between said cam and the work-crimping member and between the 20 main-shaft and the feed-dog, whereby the crimping member is actuated at one-half the frequency of the feed-dog actuations.
3. In a blind-stitching machine, the combination with a frame comprising a bracket-arm formed with hollow upright and horizontal portions and a work-supporting bed beneath said bracket-arm, a main-shaft journaled within said bracket-arm and stitch-forming mechanism comprising a reciprocating needle mounted upon the bracket-arm and a rotary loop-taker mounted upon an axis parallel with the main-shaft and having a beak whose path of movement is transverse to that of the needle, an intermediate 30 shaft, and angular gearing connecting the same at opposite ends respectively, with the main-shaft and the said loop-taker, of a work-crimping member disposed transversely to the needle-path, means for guiding 35 the same, means for imparting rising and falling movements to said crimping member, and feeding mechanism for advancing the work.
4. In a blind-stitching machine, the combination with a frame comprising a bracket-arm and a work-supporting bed, a main-shaft journaled in the bracket-arm, and stitch-forming mechanism comprising a reciprocating needle and a co-operating loop-taker both sustained by the bracket-arm and operatively connected with the forward portion 50 of the main-shaft, of a work-crimping member movable toward and away from the path of reciprocation of said needle, a cam-member connected with the main-shaft, a vibrating lever mounted upon a fixed fulcrum and deriving its movements from said cam member, a second lever mounted to vibrate concentrically with the first named 55 member and adjustably connected therewith in different angular relations thereto, operative connections intermediate the second-named lever and the said crimping member whereby the latter is moved toward and 60 away from the needle-path, and feeding mechanism for advancing the work.
5. In a blind-stitching machine, the combination with a frame comprising a bracket-arm and a work-supporting bed, a main-shaft journaled in the bracket-arm, and 70 stitch-forming mechanism comprising a reciprocating needle and a co-operating loop-taker, both sustained by the bracket-arm and operatively connected with the main-shaft, of a work-crimping member movable toward and away from the path of reciprocation of said needle, means for raising and lowering said crimping member for each alternate stitch, a feed rock-shaft journaled within and extending longitudinally of said work-supporting bed, an upwardly extending arm on said feed rock-shaft adjacent the work-crimping member and formed with a slideway, a reciprocating block mounted in said slideway, a feed-dog pivotally mounted upon 85 the upper end of said block, means for reciprocating said block in its slideway, and means connected with the main-shaft for oscillating said rock-shaft.
6. In a blind-stitching machine, the combination with a frame comprising a bracket-arm and a work-supporting bed, and a main-shaft journaled in the bracket-arm, of 90 stitch-forming mechanism comprising a needle-lever carrying a curved eye-pointed 95 needle and mounted upon a fulcrum carried by the bracket-arm and disposed transversely of the main-shaft, offset cylindrical and ball-crank pins carried by the forward end of the main-shaft, a ball-stud carried by 100 the needle-arm, a pitman connection intermediate said ball-crank pin and ball-stud, a bell-crank take-up lever having one arm connected with the cylindrical crank-pin upon the main-shaft and the other arm provided with a thread-eye, a link one end of 105 which is pivotally connected to the bracket-arm and the other end of which affords a fulcrum for the angular or central portion of said take-up, a loop-taker co-operating 110 with said needle and carried by the bracket-arm, and operative connections between said loop-taker and the main-shaft, a work-crimping member movable toward and away from the path of movement of said needle, a 115 spring-actuated presser-foot opposed to said crimping member, means for shifting said crimping member in respect to the needle-path for each alternate stitch, and feeding mechanism for advancing the work.
7. In a blind-stitching machine, the combination with a frame comprising a bracket-arm and a work-supporting bed, and a main-shaft journaled in the bracket-arm, of 125 stitch-forming mechanism comprising a needle-lever carrying a curved eye-pointed needle and mounted upon a fulcrum carried by the bracket-arm in fixed transverse

relation to the main-shaft, a ball-crank carried by the forward end of the main-shaft, a pitman connection intermediate said ball-crank and the needle-lever, a rotary loop-taker mounted in fixed bearings depending from said bracket-arm and having its axis above and in the plane of the needle-path, said loop-taker being formed with an axial thread cavity and having a clearance space 10 in front of the same, a bobbin removably sustained within the thread cavity of said loop-taker, operative connections between the main-shaft and said loop-taker, a work-crimping member movable toward and away 15 from the path of movement of said needle, a spring-actuated presser-foot opposed to said work-support, means for shifting said crimping member in respect to the needle-path for each alternate stitch, and feeding 20 mechanism for advancing the work.

8. In a blind-stitching machine, the combination with a frame comprising a bracket-arm and a work-supporting bed having an elevated forward end portion, and a longitudinally extending main-shaft journaled in the bracket-arm, of stitch-forming mechanism comprising a needle-lever carrying a curved eye-pointed needle mounted upon a

fulcrum carried by the bracket-arm and disposed transversely of the main-shaft, a 30 crank mounted on the forward end of the main-shaft, a pitman connection intermediate said crank and the needle-lever, a rotary loop-taker mounted in fixed bearings depending from said bracket-arm and having its axis arranged permanently above and in the plane of the needle-path, operative connections between the main-shaft and said loop-taker, a work-crimping member mounted in the forward end of said work-supporting bed with its operative face disposed above the elevated portion of the latter and movable toward and away from the path of movement of said needle, a spring-actuated presser-foot opposed to said crimping member, means for reciprocating said crimping member in respect to the needle-path for each alternate stitch, and feeding 45 mechanism for advancing the work.

In testimony whereof, I have signed my 50 name to this specification, in the presence of two subscribing witnesses.

MARTIN HEMLEB.
